UNITED STATES PATENT OFFICE.

WILLIAM GRONKE AND WALLACE T. ROUSE, OF CANORA, SASKATCHEWAN, CANADA.

RAILROAD-SPIKE.

977,795.

Specification of Letters Patent. Patented Dec. 6, 1910.

Application filed November 4, 1909. Serial No. 526,232.

To all whom it may concern:

Be it known that we, WILLIAM GRONKE and WALLACE T. ROUSE, subjects of the King of England, residing at Canora, in 5 the county of Saskatchewan, Dominion of Canada, have invented certain new and useful Improvements in Railroad-Spikes; and we do hereby declare the following to be a full, clear, and exact description of the invention, such as will enable others skilled in 10 the art to which it appertains to make and use the same.

This invention relates to railroad spikes and its object is to provide a novel form of 15 railroad spike which, when once inserted in a tie, may be rendered impossible of withdrawal.

With the above and other objects in view, the invention consists in general of a railroad spike provided with barbs pivoted thereto and with means to project said barbs and hold them in projected position when the spike is driven.

The invention further consists in certain 25 novel details of construction and combinations of parts hereinafter fully described, illustrated in the accompanying drawings, and specifically set forth in the claims.

In the accompanying drawings, like characters of reference indicate like parts in the several views, and :—Figure 1 is a side elevation of a spike constructed in accordance with this invention, the barbs being folded inward. Fig. 2 is a section on the line 2—2 35 of Fig. 1. Fig. 3 is a section in the same plane as Fig. 2 with the barbs shown projected.

The numeral 10 indicates the body of a spike and this spike is provided with the 40 usual head 11. The body of the spike is preferably of uniform width and thickness throughout and is provided with a tapering point 12. Extending through the body 10 is a slot 13 and from the slot 13 through the 45 top of the head 11 there extends a tubiform opening 14. Adjacent the bottom of the body 10 and opening through the slot 13 are pin receiving openings 15 and in these openings are held pins 16 whereto are pivoted 50 barbs 17 so arranged that they may close in with their outer sides flush with the sides of the body 10. The upper ends of these barbs are beveled as at 18 to form, in connection with the outer sides, cutting edges 55 while the inner sides of the barbs are provided with a series of ratchet teeth 19. Held

to slide in the opening 14 is a headed bar 20 provided with a triangular head 21 which is held in the slot 13 between the beveled portions 18 of the barbs when the latter are 60 closed in. The length of this member 20 with its head 21 is such that it may be inserted in the slot 13 and the bar or stem 20 pushed up into the opening 14. It will, of course, be necessary to do this before the 65 barbs are placed in position and the pins 16 inserted to hold them. In the upper part of the opening 14 there is provided a removable pin 22 having a head 23.

In the operation of the device the pin 22 70 is removed and the spike driven as is common with such devices. When the spike has been driven solidly to its position the pin 20 is replaced and struck with the driving hammer which results in the triangular 75 head 21 being forced down between the inner faces of the barbs. The result of this is that the barbs are projected outward while at the same time the sharp corners of the triangular head catch in the ratchet teeth 80 of said barbs. The pin 22 may then be removed and utilized for driving other barbs into position. By reason of this construction not only are the barbs projected outwardly but if the spike be driven farther 85 the barbs are prevented from closing into the slot 13 by reason of the ratchet teeth catching on the corners of the head 21 so that these barbs cannot close. By this means it is impossible to extract the spike by driv- 90 ing it in to force the barbs within their seat in the slot 13 and then withdrawing it as the barbs can never, when once projected, be made to assume such position.

There has thus been provided a simple 95 and efficient device of the kind described and for the purpose specified.

Having thus described the invention, what is claimed as new, is:

1. In a railroad spike, a body provided 100 with a through slot near its bottom extending longitudinally thereof, said body further having an opening extending from the slot upward through the head, a pair of barbs pivoted at their lower ends to the body 105 in the lower part of the slot and adapted to lie entirely therein during driving of the spike, a plunger movable in the opening, a head on said plunger to force said barbs apart when moved downward therebetween, 110 means to engage the upper end of the plunger to permit the same being driven down-

ward and means on the head and barbs to prevent retraction of the head after the plunger is forced downward.

2. In a railroad spike, a body provided with a through slot near its bottom extending longitudinally thereof, said body further having an opening connecting therewith and extending from the slot through the head, a pair of barbs pivoted at their lower ends in the lower part of the slot and adapted to lie entirely therein during driving of the spike, a plunger movable in the opening, a triangular head on said plunger to force said barbs apart when moved downward therebetween, ratchets on the inner

sides of the barbs to engage the angles on said head when the latter is moved downward, said ratchets preventing retraction of said head, and a removable pin in the upper part of the opening adapted to rest on the upper end of the plunger and force the same downward when the upper end of the pin is struck. 20

In testimony whereof, we affix our signatures, in presence of two witnesses.

WILLIAM GRONKE.
WALLACE T. ROUSE.
